UNITED STATES PATENT OFFICE.

OTTO ALBIN BUDIG, OF LILLE, FRANCE.

STABILIZING APPARATUS FOR AEROPLANES.

1,083,347.

Specification of Letters Patent.

Patented Jan. 6, 1914.

Application filed May 2, 1913. Serial No. 765,066.

To all whom it may concern:

Be it known that I, OTTO ALBIN BUDIG, a subject of the German Emperor, residing at Lille, in France, have invented certain new and useful Improvements in Stabilizing Apparatus for Aeroplanes, of which the following is a specification.

The object of this invention is to provide an automatic stabilizing appliance for aeroplanes, which is actuated by means of a vacuum created by the movement of the aeroplane.

The invention is illustrated in the accompanying drawing, in which—

15 Figure 1 is an end view of part of the stabilizing appliance, and Fig. 2 is a bottom plan view thereof. Fig. 3 is a side elevation, partly in section, showing the appliance fitted to a biplane.

20 The appliance illustrated comprises a curved hollow sustaining plane 1, which may consist of wood or sheet metal and is rigidly fixed to the flying machine, at an angle differing from that of the main planes.

25 Fig. 3 shows this small plane arranged as a separate adjunct to the machine, but it may be used instead of one of the ordinary planes, for example instead of a tail plane. The interior of the said plane communicates

30 with the interior of a cylinder 2 containing a piston 3, the latter being connected by a rod 5 to an elevating plane 4, so that the position of the latter varies with the position of the piston. The plane 1 has in its

35 convex under-surface a slot 6, which extends nearly throughout its width, and may be about 5 mm. wide or less. Except for this slot, the walls of the plane are air-tight. The piston is also made air-tight by inserting a bellows between the same and the cylinder head.

40 It is well established that the vacuum and pressure in the cavity of a bearing plane vary, within limits, with the speed and the 45 inclination of the plane. It is also known that the suctional effect is greater than the wind-pressure. What applies to the whole surface also applies to a line, so that if the slot referred to is placed in what may be

50 called a suction line, the vacuum in the interior of the plane will depend on the speed and the angle of the air pressure.

55 It has been found that the suctional effect over a certain line varies as the square of the speed, and at a wind velocity of 22 m. per sec. and inclination of 10° of the hollow

plane has the value of 10 gr. per sq. cm. At —15° inclination the suction is *nil*, at the same speed, and then increases proportionally with the angle. At about 10° the highest value is obtained. Thereafter the value falls fairly quickly.

In still air, at a constant speed, the piston, in conjunction with a spring acting on the rudder, holds the elevating plane or rudder in a predetermined position. Any reduction of speed allows the piston to move forward, and adjust the rudder more or less for descent. The aeroplane accordingly tends to regain its speed, and the rudder is raised again. The action is reversed when the speed increases.

If the inclination of the plane is altered by impact of wind, so that for example the angle of the air pressure on the plane is increased, the vacuum is reduced, the piston moves forward, and the rudder counteracts the lifting effect of the wind. If the wind acts from above, the suction increases and the rudder increases its lifting power. But this increase does not exceed a certain limit, the hollow plane being so fitted to the machine that if a powerful gust from above causes the angle of 10° to the air pressure to be exceeded, the rudder deflects the machine downward.

If an elevating rudder at the rear is to be operated by the piston, it must be arranged to receive the wind-pressure on its back surface.

According to the position of the pivot of the rudder, the sensitiveness thereof to changes of speed can be made more or less complete. The spring connected to the rudder tends to hold same horizontal, or nearly so.

I may use a plurality of cylinders, with pistons therein, all the cylinders communicating with a single hollow plane, and the pistons being connected to each other.

What I claim as my invention and desire to secure by Letters Patent of the United States is:—

1. Automatic stabilizing apparatus for aeroplanes, comprising a concavo-convex hollow plane having a slot therein, a cylinder communicating with the interior of said hollow plane, a piston in said cylinder, and means for connecting said piston to a rudder.

2. In an aeroplane the combination of a concavo-convex hollow plane arranged with

its convex wall downward, said convex wall having a slot whereby the wind of the machine creates a vacuum in said hollow plane, a cylinder communicating with the interior 5 of said hollow plane, a piston in said cylinder, an elevating rudder, and means connecting said piston to said rudder.

In witness whereof I have signed this specification in the presence of two witnesses.

OTTO ALBIN BUDIG.
